SOAP CAKE HOLDER

Ernest F. James, 1807 W. Northview, Phoenix, Ariz.
Filed Apr. 8, 1963, Ser. No. 271,060
7 Claims. (Cl. 45—28)

This invention relates to a soap cake holder and more particularly to a novel soap cake holder having a flexible foraminous fabric soap cake supporting structure carried by a semirigid outline frame having poleless portions which are abridged by the fabric soap cake support.

Various soap cake holders have been utilized to drain moisture away from a soap cake after use so that the soap cake readily dries and does not dissolve at an unwarranted rate.

Conventional soap cake holders usually comprise a tray or grid structure designed to support a soap cake and to permit drainage therefrom, however, many of the soap cake holders now in use are difficult to clean since dried soap tends to collect on the grid structure of soap cake holders which are made of rigid material.

Many of the prior art soap cake holders are made of rigid material and consequently are quite heavy, thus requiring strong fixtures or permanent incorporation into bathroom wall or tub structures.

Accordingly, it is an object of the present invention to provide a novel soap cake holder composed of an outline frame of semirigid material having spaced frame portions over which an abridging flexible foraminous fabric is supported thereby providing a very light weight soap cake holder which is easy to clean and which may be supported by vacuum cups or other simple supporting structure in connection with the great variety of smooth or other surfaces.

Another object of the invention is to provide a soap cake holder having a frame from which a flexible foraminous cover is readily removable so that it may readily be washed after having supported soap cakes for a given period of time.

Another object of the present invention is to provide a novel soap cake holder which may be composed or constructed of a simple outline wire frame and flexible foraminous fabric material such as cotton cloth of various kinds.

Another object of the invention is to provide a novel soap cake holder having a very novel wire frame structure provided with loop portions coupled to conventional vacuum cups for conveniently supporting the soap cake holder of the invention on various surfaces.

Another object of the invention is to provide a novel soap cake holder composed of a plurality of continuous coils of wire between which a flexible fabric foraminous material is clamped thereby to provide a novel means for supporting the flexible material and to permit a simple means for removing and replacing the fabric material for cleaning it while permitting the frame to be fixed in a stationary position.

Another object of the invention is to provide a novel soap cake holder having an outline frame abridged by soft flexible foraminous fabric whereby the soap cake may be supported between the spaced frame members and on the flexible foraminous fabric structure so that the soap cake after being wet and placed on the fabric

2

will be efficiently aerated and dried without causing a substantial amount of the soap cake to be dissolved.

Another object of the invention is to provide a novel soap cake holder having an outline frame on which a soft flexible foraminous fabric material may be supported for holding a soap cake; said material being adapted for use as a wash cloth preliminary to replacement thereof in connection with the frame and for supporting the soap cake thereon.

Another object of the invention is to provide a novel soap cake holder composed of a simple wire frame which may be made by an automatic wire machinery and a soft flexible foraminous fabric stretcher which may readily be detachably secured to the frame.

10 Further objects and advantages of the invention may be apparent from the following specifications, appended claims and accompanying drawings in which:

FIG. 1 is a side elevational of a soap cake holder in accordance with the present invention showing portions thereof broken away and in section to amplify the illustration and showing a soap cake supported on the flexible foraminous fabric structure of the holder;

FIG. 2 is a sectional view taken from the line 2—2 of FIG. 1;

25 FIG. 3 is a side elevational view similar to FIG. 1;

FIG. 4 is an enlarged fragmentary sectional view taken from the line 4—4 of FIG. 1;

FIG. 5 is a sectional view taken from the line 5—5 of FIG. 1;

30 FIG. 6 is a bottom view of a modified soap cake holder of the invention;

FIG. 7 is a fragmentary elevational view taken from the line 7—7 of FIG. 6; and

FIG. 8 is an elevational view taken from the line 8—8 35 of FIG. 6.

As shown in FIG. 1 of the drawings the soap cake holder of the invention is provided with a frame 10 which may be made of wire or any other suitable material, as for example this frame may be formed plastic or cast of any other material as desired.

The particular and preferred structure shown comprises wire which is preferably of stainless steel or other material which is substantially noncorrosive.

The frame 10 as shown in FIG. 5 of the drawings is provided with spaced frame portions 12 and 14 which are substantially parallel to each other and also spaced frame portions 16 and 18 which are substantially parallel to each other, all of said frame portions being formed in a single continuous piece of wire to provide a rectangular open outline frame structure which is abridged by a soft flexible foraminous fabric 20 which may be of various materials such as cotton, synthetic materials or any suitable material which is foraminous and in accordance with the following requirements.

45 The spaced frame portions 12 and 14 are provided with loops 22 and 24 which support shank portions 26 and 28 of vacuum cups 30 and 32; these are conventional vacuum cups having concave surface portions 34 and 36 adapted to be coupled in the conventional way to a smooth surface 38 which may be any suitable surface so desired, as for example adjacent a sink, shower, tub or other household fixture or appliance.

50 The frame 10 is also provided with integral loops 40 and 42 disposed to receive shanks 44 of the vacuum cups

46, the plane of the loops 40 and 42 being at substantially at 90 degrees to the loops 22 and 24.

With a comparative reference between FIGURES 1 and 3 of the drawings it will be seen that the vacuum cups 30 and 36 supported by the loops 22 and 24 are adapted to hold the soap cake holder of the invention on a horizontal surface 38 and that vacuum cups 36 coupled to the loops 40 and 42 are disposed to hold soap cake holder of the invention in connection with a substantial vertical surface 48, thus the loops 40 and 42 are disposed at substantially right angles with respect to the loops 22 and 24; these loops 40 and 42 are formed integral with the wire structure of the frame 10, all as shown best in FIGURES 2 and 3 of the drawings.

The frame 10 is provided with upwardly directed loops or folded portions 50 which are disposed at corners 52, 54, 56 and 58 of the frame 10.

Additionally, intermediate upwardly extending loops 60 and 62 are formed in the side frame portions 16 and 18 so that all of these upwardly extending loop portions are disposed to support and hold removable structure of the fabric 20.

As shown in FIGURES 1, 2, 3 and 5, the fabric structure 20 is provided with spaced channel shaped portions 64 and 66 which are formed by sewing opposite side portions 68 and 70 and 72 and 74 of these channel portions together but leaving open portions in the hem for the loop portions 50 to project upwardly into the channel portions 64 and 66, thus these channel portions 64 and 66 provide upwardly extending sides opposite side frame portions 16 and 18 of the frame 10 and the soap cake is supported on the upper surface of the foraminous fabric 20 as shown best in FIG. 1 of the drawings.

It will be seen that the fabric channels having spaced open portions in the stitching provide pockets for the upwardly extending loops 50 to thereby form a removable support of the flexible fabric structure 20 and the frame 10.

It will be appreciated that this soap cake holder is a very light weight structure composed of the semirigid outline wire frame and the foraminous flexible fabric cover and that the cover itself may be used as a wash rag which provides a utilitarian structure which between uses supports a soap cake and during the use is automatically cleaned by washing action accomplished by use of the cover as a wash rag.

The facility of washing the fabric structure 20 will be appreciated by those skilled in the art since the usual fixed rigid grid structure of soap cake holders is very difficult to clean and must be engaged by a brush or by another instrument properly to accomplish such cleaning operations, thus the simple cleaning operation of the fabric structure 20 of the invention and its simple removability from the frame 10 renders the soap cake holder of the invention very novel and useful.

In the modification of the invention as shown in FIGURES 6 to 8 of the drawings an outline frame 76 is preferably made of wire and is formed into a pair of contiguous coil loops 78 and 80 much similar to adjacent coils of a closed loop coil spring. These coil loops 78 and 80 are formed in a single continuous piece of wire having one free end 82 and a second free end 84. The free end 84 forms a terminus of a cross member 86 which extends across the outline frame 76 and this cross member 86 is provided with a pair of loop portions 88 and 90 disposed to hold shanks of vacuum cups 92 and 94, respectively, which are adapted to support the frame 76 on a horizontal surface 96 as shown on FIGURES 7 and 8 of the drawings.

In the row with the loop portions of 78 are second loops 98 and 100 adapted to support vacuum cups 102 for supporting the frame 76 on a substantially vertical surface 104.

Fabric structure 106 similar to the fabric 20 is clamped between the contiguous coil loops 78 and 80 which surround the area of the fabric 106 opposite edges 108 and

110 of the fabric 106 project beyond the extremities of the frame 76 and the resilient character of the coil loops 78 and 80 holds the fabric structure 106 securely in abridging relation with the outline frame so that a soap cake 112 may be supported on the fabric 106 in an area surrounded by the outline frame.

The free end 84 of the cross member 86 is supported in and surrounded by a loop 114 of the coil loop 78 all as shown best in FIGURES 6 and 7 of the drawings, thus the loops 90 and 92 are held in such a position by the bar 86 so that the vacuum cups 92 and 94 firmly support the soap cake holder of the invention and particularly that of modification shown in FIGURES 6, 7 and 8 of the drawings.

It will be obvious to those skilled in the art that various modifications of the present invention may be resorted to in a manner limited only by just interpretation of the following claims.

I claim:

1. In a soap cake holder the combination of: an outline frame having spaced frame portions substantially surrounding an area and flexible foraminous fabric material removably supported on substantially coextensive with and abridging said spaced frame portions and substantially covering said area; upstanding portions on said spaced frame portions; portions of said fabric material fitted over said upstanding portions said frame open below said fabric material.

2. In a soap cake holder the combination of: a wire frame; and fabric material supported thereon and disposed to support a soap cake; continuous coil structure of said wire frame having a plurality of resilient integral normally contiguous coils and substantially surrounding an area; said fabric material clamped between said normally contiguous coils and bridging said area said frame open below said fabric material.

3. In a soap cake holder the combination of: a wire frame; and fabric material supported thereon and disposed to support a soap cake; continuous coil structure of said wire frame having a plurality of resilient integral normally contiguous coils and substantially surrounding an area; said fabric material clamped between said normally contiguous coils and bridging said area; a loop on one of said coil structures; and a vacuum cup fixed to said loop said frame open below said fabric material.

4. In a soap cake holder the combination of: an outline frame having spaced frame portions substantially surrounding an area and flexible foraminous fabric material removably supported on substantially coextensive with and abridging said spaced frame portions and substantially covering said area; upstanding portions on said spaced frame portions; portions of said fabric material fitted over said upstanding portions; a vacuum cup secured to said outline frame said frame open below said fabric material.

5. In a soap cake holder the combination of: a wire frame; and fabric material supported thereon and disposed to support a soap cake; continuous coil structure of said wire frame substantially surrounding an area; said fabric material clamped between said coil and bridging said area; a crossbar integral with one of said coil structures and extending transversally across said area; a free end of said crossbar supported by said coil structure; a loop of said last mentioned coil structure surrounding said free end of said crossbar said frame open below said fabric material.

6. In a soap cake holder the combination of: a wire frame; and fabric material supported thereon and disposed to support a soap cake; continuous coil structure of said wire frame substantially surrounding an area; said fabric material clamped between said coil and bridging said area; a crossbar integral with one of said coil structures and extending transversally across said area; a free end of said crossbar supported by said coil structure; a loop of said last mentioned coil structure surrounding said free end of said crossbar; a support loop integral with said

crossbar; and a vacuum cup secured to said support loop said frame open below said fabric material.

7. In a soap cake holder the combination of: an outline frame having spaced frame portions substantially surrounding an area and flexible foraminous fabric material removably supported on substantially coextensive with and abridging said spaced frame portions and substantially covering said area; upstanding portions on said spaced frame portions and channel shaped seamed portions of said flexible fabric fitted over said upstanding portions and

5 forming opposed upstanding side structures for said soap cake holder said frame open below said fabric material.
